CLAIM

The ornamental design for a container top, as shown and described.

DESCRIPTION

FIG. 1 is a top perspective view;

FIG. 2 is a front view;

FIG. 3 is a back view;

FIG. 4 is a right side view;

FIG. 5 is a left side view;

FIG. 6 is a top view;

FIG. 7 is a bottom view; and,

FIG. 8 is an alternate top perspective view.

The dashed lines depict portions of the container top that form no part of the claimed design.

1 Claim, 8 Drawing Sheets
